DESIGN FOR A SCOOTER

John Delbert Wheeler, Detroit, Mich., assignor to American Metalcraft Corporation, Detroit,
Mich., a corporation of Michigan

Application July 22, 1946, Serial No. 131,815

Term of patent 14 years

(Cl. D34—15)

To all whom it may concern:

Be it known that I, John Delbert Wheeler, a citizen of the United States of America, residing at Detroit, in the county of Wayne and State of Michigan, have invented a new, original, and ornamental Design for a Scooter, of which the following is a specification, reference being had to the accompanying drawing, forming a part thereof, wherein:

The figure is a perspective view of a scooter, showing my new design.

The essential features of my design reside in the portions shown in full lines on the drawing.

I claim:

The ornamental design for a scooter, as shown and described.

JOHN DELBERT WHEELER.
